UNITED STATES PATENT OFFICE.

FREDERICK ARTHUR ALCOCK, OF ARMADALE, NEAR MELBOURNE, VICTORIA, AUSTRALIA.

COMBINED TALKING-MACHINE CABINET AND WRITING DESK.

Application filed May 19, 1923. Serial No. 640,260.

To all whom it may concern:

Be it known that I, FREDERICK ARTHUR ALCOCK, a British subject, residing at No. 14 Denbigh Road, Armadale, near Melbourne, 5 in the State of Victoria, Commonwealth of Australia, have invented new and useful Combined Talking-Machine Cabinets and Writing Desks, of which the following is a specification.

10 This invention relates to a combined talking machine cabinet and writing desk and has been devised with the object of effecting improvements in the construction of talking machine cabinets and of incorporating or 15 combining a writing desk therewith.

In this invention one of the improvements consists in so constructing the cabinet that the top of same is made a fixture and which provides a suitable rest or stand for flowers, 20 ornaments and the like, the machine chamber and the horn chamber lying side by side or adjacent to one another. A further improvement comprises the provision of a horn extension or amplifier to convey the sound 25 from the tone arm to the adjacent horn compartment and which extension passes diagonally from the front of the machine compartment where it is in communication with the tone arm to the rear of the cabinet 30 to said horn compartment, and which extension, it is found, gives added beauty and an improved tone resonance.

In the accompanying drawings:—

Fig. 1 is a front elevation of the combined 35 talking machine cabinet and writing desk constructed according to my invention.

Fig. 2 is a plan taken on line *a—a* of Fig. 1 which shows the position of the diagonally disposed horn extension or amplifier which 40 passes from underneath the tone arm in front of the machine compartment to the back of the horn compartment.

Fig. 3 is a plan of portion of a tone regulator or muffler employed.

45 In the drawings A represents a fixed top or cover of the cabinet and B and C represent two compartments, the compartment B housing the talking machine and herein-after referred to as the machine compartment, and C a compartment having a horn built therein, and herein-after referred to as the horn compartment, both compartments being positioned side by side or adjacent to one another.

55 The machine compartment B is provided

with a horizontal partition *B*² the motor F of the talking machine being positioned underneath the said partition which latter is provided with a central opening *F*¹ to receive the motor spindle (not shown) which carries the turntable *d*. In this construction, the tone arm D of the machine is positioned over an opening in the partition *B*² at the front of and adjacent to the side of the cabinet as at *d*¹, in order that the tone arm may be swung outside its compartment *b*¹ to permit of the records being conveniently placed on the turntable *d* and to facilitate the insertion and removal of needles. E is the amplifier or horn extension which passes 65 from under the tone arm *d*¹ and diagonally across the cabinet to the rear of the horn compartment C. The motor F for revolving the turntable *d* is provided with the usual winding shaft and crank handle 70 *d*² which is shown extending through one side of the cabinet.

Underneath the machine and horn compartments a combined pigeon hole and writing desk compartment *b* is provided, the 80 upper half of which compartment contains a number of pigeon holes or divisions for the reception of stationery, pens, ink and the like, while the lower half is utilized to house a writing desk H which latter is slidably 85 mounted in the guides *h*, secured to the inner surfaces of the cabinet.

A hinged panel I is provided and which, when in its vertical or closed position, completely covers the writing desk compartment 90 but which panel has to be first drawn down to a horizontal position in order to provide a support for the writing desk after which the latter is pulled out to its fullest extent. The writing desk and panel are provided with 95 gripping knobs *h*¹ and *i* respectively, the panel being provided with a catch (not shown) for locking said panel in its closed position.

The lower part of the cabinet is devoted 100 to a divided compartment G for storing such as records and the like, two hinged doors J being provided to cover the front of same.

The muffler or tone control employed 105 consists of a flat wooden member *e*¹ which is slidably operated by means of a rod *e* projecting beyond the side of the cabinet. The member *e*¹ is adapted to slide over a horizontal section or opening *w* of the horn 110

extension adjacent to the rear opening C and is provided with a flat surface e^2 which can be gradually brought over the opening α to reduce the tone, the adjacent opening e^3 in 5 the member e^1 , when brought to coincide with the opening α , permitting the uninterrupted passage of the sound therethrough.

The member e^1 is adapted to slide between the guides e^4 supported in the horn compartment C.

The horn compartment in the cabinet is suitably covered with a skeleton framework on a silk background (not shown) to present an ornate appearance and to allow for 15 the passage of the sound from the horn.

The cabinet is preferably rectangular in shape and is supported on four legs, as shown.

Having now described my invention what 20 I claim as new and desire to secure by Letters Patent is:—

A talking machine cabinet having a top and providing two front-opening compart-

ments arranged side by side directly under said top, a forwardly extending horn in 25 one of said compartments, a talking machine in the other compartment, said last named compartment having a floor, the talking machine turntable and tone arm being accessible below the top and above the floor 30 and through the compartment front, said tone arm being arranged forwardly within said compartment and swingable outwardly, and an elongated transverse horn extension arranged below said floor and at one end 35 extending into the horn compartment and opening upwardly into the rear end of the horn and at its opposite end opening upwardly through said floor into said tone arm.

In testimony whereof I have signed my 40 name to this specification in the presence of two subscribing witnesses.

FREDERICK ARTHUR ALCOCK.
